UNITED STATES PATENT OFFICE.

GEORGE SOYLIAN, OF BROOKLYN, NEW YORK.

CLOTH-LAYING MACHINE.

1,333,459.

Specification of Letters Patent.

Patented Mar. 9, 1920.

Application filed October 18, 1918. Serial No. 258,679.

To all whom it may concern:

Be it known that I, GEORGE SOYLIAN, a citizen of the United States, and a resident of the city of New York, borough of Brooklyn, in the county of Kings and State of New York, have invented a new and Improved Cloth-Laying Machine, of which the following is a full, clear, and exact description.

This invention relates to cloth laying machines and has for an object an arrangement which will automatically lay any desired length and thickness of cloth quickly and accurately.

Another object of the invention is the provision of an improved construction which is simple but accurate in operation and which will lay cloth from a roll or from a previously laid supply of cloth.

A further object of the invention, more specifically, is the provision of an improved arrangement which will grip the ends of the cloth as the cloth is laid and which will also automatically shift the laying mechanism according to the thickness of the laid cloth.

A still further object of the invention is the provision of an improved arrangement whereby when the power is turned on the laying mechanism will continue to operate until the power is turned off without any action on the part of the operator so that when the machine is once started a complete roll of cloth may be laid without effort on the part of the operator.

In the accompanying drawings:

Fig. 1 is a side view of a machine disclosing an embodiment of the invention, certain parts being broken away.

Fig. 2 is a top plan view of the structure shown in Fig. 1.

Fig. 3 is a side view of the carriage shown in Fig. 1, but looking at the same from the opposite side.

Fig. 4 is a view similar to Fig. 5, but on a reduced scale showing the carriage going in the opposite direction to that indicated in Fig. 5.

Fig. 5 is a sectional view through Fig. 2 on line 5—5, the same being on a slightly enlarged scale.

Fig. 6 is a fragmentary sectional view through Fig. 3 on line 6—6.

Fig. 7 is a detail on line 7—7 of Fig. 1 indicating the means for adjustably clamping the stationary transverse bars to the table.

Fig. 8 is a fragmentary longitudinal ver-

tical section through the upper part of a slightly modified form of carriage to that shown in Fig. 3 when a bundle of laid cloth is carried for the purpose of relaying.

Referring to the accompanying drawings by numerals 1 indicates a table which may be any desired kind, but preferably a smooth structure for supporting the various traction wheels 2 and for supporting certain other parts of the machine hereinafter fully described. The traction wheels 2 are preferably four in number as shown in the drawing and flanged so that the carriage 3 will not move off of the table 1. The carriage 3 is provided with end frames 4 connected by suitable bars whereby a rigid frame work is produced for supporting the various parts of the laying mechanism. Arranged at one end of the carriage 3 is an electric motor 5 for operating a worm 6 which meshes with the worm wheel 7 also supported on the carriage 3. Worm 7 is connected with a shaft 8 carrying a sprocket wheel 9 which accommodates the chain 10, which chain in turn passes over a suitable sprocket wheel 11 secured to one of the flanged wheels 2. The shaft 8 extends entirely across the carriage 3 as shown in Fig. 2 and has a sprocket wheel 9' rigidly secured thereto for accommodating a chain similar to chain 10 whereby two of the flanged wheels 2 will be positively driven for propelling the carriage 3 back and forth on table 1. The motor 5 is supplied with current from the supply wire 12, which current may be turned on and off by a manually operated switch 13. The current passes not only through switch 13, but through an automatic switch 14 and a rheostat 15 before passing into the motor 5. The automatic switch 14 is a pole changing switch and is connected with a reciprocating bar 16, which when in the position shown in Fig. 1 causes the motor 5 to run in one direction and when moved by the stop 17 will cause the motor to operate in the opposite direction. As shown in Fig. 1 the carriage is moved toward stop 17 and as soon as the bar 16 strikes its stop it will be moved horizontally and guided by pins 18 and 19 operating in slots 20 and 21 so that the switch 14 will be changed and all of the moving parts will be reversed, the carriage then will move in a reverse direction until it strikes the stop 22 whereupon bar 16 will be again moved for shifting the pole changing switch 14 and the parts reversed to move back to

ward stop 17. The bar 16 has been mentioned as being moved by these stops, but it will be evident that the bar in striking the stops 17 and 22 respectively will stand still 5 and the other parts will move which will have the effect above described. This mechanism will cause the carriage to move back and forth as long as current is supplied and will consequently provide layers of cloth on 10 the table 1 until the entire roll 23 has been exhausted. When this has occurred switch 13 is operated for shutting off the current so that the carriage will stop, but if for any reason the current should not be switched off 15 the carriage will continue to operate but without laying any additional cloth or without affecting the cloth already laid.

At each end of the table 1 is a gripping bar 24 extending transversely of the table 20 as shown in Fig. 2, said gripping bar coacting with a gripping platform 25. A pair of arms 26 are rigidly secured to the gripping bar and are connected with a shaft 27 which extends through the slots 28 in 25 the respective posts 29 and 30. These posts are bolted or otherwise rigidly secured to table 1 in any desired manner. Preferably, these posts are bolted to a transverse bar 31 as shown in Fig. 2 which is provided with 30 a pair of guideways at each end for receiving the sliding plates 32 and 33 which in turn carry the stops 17. Each of these stops comprises a tubular member 34 rigidly secured to part of the slide 32 and bar 35 35 having an enlarged end 36 against which the spring 37 presses. Spring 37 also presses against the closed end of the tubular member 34, said closed end being formed with an opening through which the bar 35 passes as shown in Fig. 5. This construction 40 is such that when the bumper 17 or the bumper 22 is hit there will be a yielding action in order not to throw the switch 14 over at too great a speed or too suddenly. 45 The arrangement of gripping bars, posts and associate parts at each end is identical so that the description of one will apply to all. However, near one end of the table 1 is arranged an inclined guide 38 which is 50 adapted to engage the roller 39 on rod 40 for elevating said rod whereby certain adjusting mechanism will be operated so as to take care of the pile of goods that has been laid as hereinafter fully described. Opposite the guide 38 a resilient stop 41 is provided coacting with the lever 42. When lever 42 strikes the stop 41 said lever will be thrown over to its opposite position and as the carriage moves on the lever will snap 55 past the stop so as to be again moved when the carriage returns. The lever 42 as shown in Fig. 5 is pivotally mounted at 43, the pivotal pin being adjustably mounted in slot 44 so that proper adjustment may be 60 had at any time. When the lever 42 is

moved by reason of its contact with stop 41 it will in turn move the rack 45 which meshes with the gear 46 rigidly secured to shaft 47. By this arrangement the shaft 47 is rotated whenever the lever 42 is moved and it is rotated in a direction corresponding to the movement of the lever. However the pivotal pin at 43 is arranged in slot 44 so as to allow an upward adjustment of the lever 42 by means hereinafter fully described, so that whether the shaft 47 is in an upper or lower position it will be properly operated. The shaft 47 is journaled in suitable brackets or rack bars 48 held in proper position by suitable guides 49, there 70 being one rack bar adjacent each side of the frame 3. The rack bars 48 continually mesh with pinions 50 which are rigidly secured to shaft 51, said shaft extending through one of the side frames and having 75 connected therewith a worm gear 52 as shown in Fig. 3, said worm gear meshing with worm 54 mounted on shaft 55. This shaft carries a clutch face 56 adapted to mesh with the clutch face 57 secured to the gear 58 which meshes with the rack 59 on the bar 40. By this construction bar 40 is raised by the guide 38, shaft 55 will be rotated somewhat and consequently power will be transmitted to the shaft 51 and to the respective racks 80 48 for elevating the same slightly. At each complete back and forth movement of the carriage rod 40 will be elevated by guide 38 and then allowed to move downward again under the action of gravity. This 85 upward movement will give a rotary movement for a short time to shaft 55 upon each complete cycle of the carriage, so that each time two layers of cloth have been laid the racks 48 and shaft 47 will be raised. The 90 raising of the rack just mentioned will affect the laying blocks 60 and 61 as they will be permanently raised by each upward movement of the rod 40. However, there is a temporary up and down movement of the 95 laying bars 60 and 61 so that when the parts are arranged as shown in Fig. 5 bar 60 will be in a lowered position for laying the end of the cloth beneath the gripper bar 24 at the right end of the table 1 while 100 when the parts are in the position shown in Fig. 4 the laying bar 61 is in a lowered position for receiving the cloth in the gripper bar at the opposite or left end of the table as shown in Fig. 1. In order to 105 cause this up and down movement of these laying bars they are rigidly secured to vertically positioned rods 62 and 63 at each side of the machine said rods being connected at the upper end by a sprocket chain 110 64 passing over sprocket 65. The bars 60 and 61 of course extend for the full width of the carriage 3 so that the rods 62 and 63 at each end will bodily raise and lower these 115 bars at the proper time. It will be noted 120 64 had at any time. When the lever 42 is

that the sprocket wheel 65 at each side of the machine is mounted on the shaft 47 and is rigidly secured thereto so as to be rotated when the rack 45 is moved under the action of lever 42. From this it will be seen that when the carriage reaches the left end of the table 1 as shown in Fig. 1 lever 42 will be moved over to the right for depressing the bar 61 so that it may properly lay the cloth beneath the gripper bar 24'. As the bar 42 snaps past the stop 41 it will almost immediately thereafter reverse the action and move bar 61 upwardly and bar 60 downwardly. This movement, however, does not take place until the carriage has left the gripper bar 24 a short distance so that the laying action will be continuous and the various operations will not overlap. The bars 24 and 24' are lifted in turn by the bars 60 and 61 through anti-friction rollers 60^a and 61^a thereon.

From Figs. 1 and 5 it will be observed that several layers of fabric have been already placed in position and that the gripper bar 24 is acting to grip another layer. In Fig. 5 it will be observed that the cloth extends from the piled material 66 around the bar 60 over one end of the clamping bar 24 and from thence around the tension rollers 67 and 68 mounted on a pair of supporting cross bars 69. From the roller 68 the cloth extends to the roll of cloth 23 mounted on a roller 70 rotatably positioned on the upper part of the carriage 3.

In Fig. 8 will be seen a slight modified form of the invention in which the frame 3 is provided with a cloth support or rest 71 so as to receive a batch of cloth 72 which has been previously laid, but of a different length from that desired. The cloth from the batch 72 is fed over guiding rollers 73 and 74 and the rollers 67 and 68 and from thence through the machine as heretofore described. In this way either cloth in rolls or in bundles may be properly laid any length. In connection with laying the cloth any length it will be observed that the length of the cloth to be laid is determined by the position of the bars or plates 31 and the gripping bars 24 and 24'. These may be adjusted back and forth along the table 1 to any desired extent within the limits of the length of the table. In order to take care of the increasing thickness of the pile 66 of cloth which has been laid the gripping bars 24 are not only pivotally mounted by reason of the arrangement of the arms 26, shaft 27 and associate parts, but the shaft 27 moves upwardly as the gripping bars are moved upwardly by the action of the bars 60 and 61 so that there will always be plenty of gripping action by reason of the weight of the gripping bars, but the gripping bars always maintained in position for properly exerting this weight. As will be observed

particularly in Fig. 2 the gripping bars 25 and 25' may be adjusted toward and from each other, said adjusting means may be of any kind, the particular structure being shown in Fig. 7 as comprising clamps 22^a 70 embracing the edges of the table 1. The clamping bars 25 and 25' are likewise adjustable by bolts which are preferably positioned in the slots used by the bars 31. When the clamping bars are properly adjusted 75 shaft 55 is operated manually by a suitable crank connected therewith so as to bring the parts back to their starting position and then the cloth is placed in position for operation after which the current is turned on 80 and left on until all of the cloth or as much as desired has been properly laid.

What I claim is:

1. In a cloth laying machine of the character described a pair of spaced gripping means, a table supporting said gripping means, a carriage movably mounted on said table, a pair of laying bars arranged on said carriage, there being one laying bar for each gripping member so as to force a section of cloth between the respective gripping members as the carriage approaches, a pair of vertically movable rods connected to said laying bars, a chain connecting the upper end of said vertically movable rods, a 95 sprocket wheel engaging said chain, and means for rocking said sprocket wheel so as to successively move upwardly and downwardly said gripping bars whereby they may come opposite their respective gripping 100 members.

2. In a cloth laying machine of the character described a supporting table, a carriage for supporting a supply of cloth, a pair of laying bars for guiding the cloth 105 as it is folded back and forth, means for raising and lowering said bars successively so as to cause a proper bend, said means including a gear wheel, a rack meshing with said gear wheel, a lever on the carriage for 110 actuating said rack, and a stop positioned on said table for causing the actuation of said lever as said carriage moves back and forth.

3. In a cloth laying machine of the character described, a supporting table, a carriage for supporting a supply of cloth, means for moving the carriage back and forth over said table, gripping means on said table on opposite sides of the carriage for 115 gripping the loop of cloth as it is folded, a pair of laying bars for guiding the cloth as it is folded, means for raising and lowering said laying bars so as to properly engage the cloth during the laying action, means for 120 raising permanently said bars on each reciprocation of the carriage, said means including a rack associated with said bars, a pinion meshing with said rack, a driving mechanism for said pinion including a 125 130

- 5 ratchet wheel, a reciprocating rack bar meshing therewith, an inclined way engaging the lower end of said rack bar for operating the same upon each complete reciprocation of the carriage, and a manually actuated member for operating said ratchet wheel and the parts connected therewith for lowering said laying bars when starting a new pile.
- 10 4. In a cloth laying machine of the character described a supporting table, a carriage movably mounted on said table, spaced gripping means mounted on said table, means for supporting a supply of cloth on said carriage, a pair of laying bars for holding said cloth as the carriage reaches either of its extreme positions in its

back and forth movement, means for supporting said bars, said means including a supporting rack, automatic means for actuating said rack for moving the same upwardly permanently upon each back and forth movement of said carriage so that the laying bars gradually move upwardly permanently as the supply of laid cloth increases, and auxiliary means for moving said laying bars both upwardly and downwardly during the back and forth movement of the carriage for causing one of the laying bars to enter one of the gripping means when the carriage is at one end of its travel while the other laying bar passes over said gripping means.

20 25 30
GEORGE SOYLIAN.
